UNITED STATES PATENT OFFICE.

CHARLES H. NORTON, OF WORCESTER, MASSACHUSETTS, ASSIGNOR TO NORTON
GRINDING COMPANY, OF WORCESTER, MASSACHUSETTS, A CORPORATION OF
MASSACHUSETTS.

CYLINDRICAL GRINDING-MACHINE.

1,045,877.

Specification of Letters Patent.

Patented Dec. 3, 1912.

Application filed March 20, 1912. Serial No. 685,074.

To all whom it may concern:

Be it known that I, CHARLES H. NORTON, a citizen of the United States, residing at Worcester, in the county of Worcester and 5 State of Massachusetts, have invented a new and useful Cylindrical Grinding - Machine, of which the following is a specification.

This invention relates to that class of cylindrical grinding machines in which the 10 grinding wheel is bodily movable toward and from the work. Ordinarily these machines have been so constructed that the wheel was moved back and forth by hand.

The principal objects of this invention are 15 to provide a simple and convenient means for operating the wheel, either by hand or power, at will; to provide a construction in which the hand operated mechanism can be disconnected very readily from the wheel 20 operating mechanism when it is to be operated by power; and especially to provide a simple and effective means whereby when the wheel has been brought up by power to the limiting position it cannot be moved farther in that direction by power, until the 25 machine is reset, so that danger of bringing it too far up after truing the wheel or replacing it is avoided.

The invention also involves improvements in combinations of parts and details 30 of construction as will appear hereinafter.

Reference is to be had to the accompanying drawings, in which—

Figure 1 is an elevation of a wheel case 35 showing the wheel in contact with the work. Fig. 2 is a transverse sectional view through the wheel operating shaft and connected parts, and Fig. 3 is an elevation of the same partly in section.

The invention is shown as applied to a 40 machine in which the work A is operated upon by a rotary grinding wheel B arranged in a casing C. The means for rotating the grinding wheel are not illustrated herein as 45 the invention can be used on any ordinary type of grinding machine. Ordinarily the wheel and wheel casing are moved very slowly toward and from the work by an arrangement comprising a rotary handle 10, a 50 long-faced pinion 13 and a gear 14 on a shaft 15 which carries a worm 16 for moving the casing C back and forth. Ordin-

narily this gear 14 is connected directly with the shaft, but in this case these connections are modified as will appear hereinafter. 55

The power operating means for moving the casing C is shown as comprising a handle 20 on an oscillatable shaft 21 which is provided with a lever 22 connected with a reciprocable rod 23 carrying springs 24 and 60 an operating member 25 for operating a double faced clutch 26. This clutch is designed to connect the feed drive shaft 27 with a shaft 28 through a set of bevel gears 29 for the purpose of rotating the shaft 28 65 in either direction from the feed drive shaft. This shaft 28 is connected by any suitable gearing 29 with the shaft 15.

It will be seen, therefore, that by the mechanism so far described, the shaft 15 can 70 be rotated in either direction by the power or by hand, independently of each other. The shaft 15 is connected with the wheel 14 by a hub 30 keyed to the shaft and having rotatably mounted thereon a bushing 31 for 75 the hub of the gear and provided with a pair of circumferential grooves 32. Radial pins 33 in the hub of the gear 14 are pressed inwardly by a circumferential spring 34 so as to engage in either one of said grooves. 80 The gear is provided with a projecting flange 35 adapted to be grasped by the hand for the purpose of moving the gear back and forth so as to bring it into either of its two positions on the bushing 31. In the position 85 shown in the drawings, teeth 36 on the hub of the gear engage between teeth 37 on the hub 30 and consequently the rotation of the pinion 13 is transmitted positively to the shaft 15 or vice versa. But when the flange 90 35 is pulled back so that the pins 33 engage in the other groove 32, there is no engagement between these teeth and consequently the shaft 15 can operate without spinning the rotary handle 10 around. 95

On the hub 30 is arranged a bushing 38 by means of a screw or the like 38^a on which is carried a pinion 39. This pinion meshes with two gears 40 and 41. One of these gears 40 is fixed with respect to a bearing 42 on the frame in which the shaft 15 rotates. The other gear 41 is rotatable on this bearing and carries with it a larger gear 43. The two gears 40 and 41 are of 100

the same size so that they can both mesh with the pinion 39, but they are provided with different numbers of teeth. Preferably one of them has one more tooth than the other. The gear 43 meshes with a gear 44 which is mounted to rotate freely on a bearing 45 on the frame, this bearing being concentric with the gear 13, preferably. This gear 44 is provided with a conical friction surface 46 which is engaged by a similar surface 47 on a wheel 48 also free to rotate on the hub of the gear 44. This hub is provided with screw-threads on which is a pilot wheel 49 adapted to screw up on the threads and force the wheel 48 inwardly so as to cause the two friction surfaces to engage each other firmly and cause the gear 44 and wheel 48 to rotate together. On the wheel 48 is a block 50 which, when in one position, engages a sliding rod 51 mounted in a bearing 52 of the frame and moves it into a position in which it will engage a projection 53 on the shaft 21 and prevent the movement of this shaft beyond the center of its oscillation. That is, it will prevent the handle 20 being turned to a position to connect the clutch 26 with the shaft 27 to rotate the shaft 15 in one direction, that is the direction to move the wheel toward the work. On both the wheel 48 and a concentric surface of the frame are permanent marks as 54 and 55. Now when the grinding wheel has been brought up to position toward the work, and has to be withdrawn for truing up or any other purpose, it is obvious that it will be necessary to bring the wheel back exactly to the same point. Consequently, the operator loosens the pilot wheel 49 and turns the wheel 48 until the marks 54 and 55 register. Then the block 50 comes into the position shown in Fig. 3 and just above described. Then he tightens up the pilot wheel. This having been done it will be obvious, first that the grinding wheel cannot be moved any farther toward the work by power on account of the position of the parts 50, 51 and 52, and second, that when it has been moved away from the work and then brought up again, the block 50 will always come back to this position when the wheel comes back to its original extreme position. In this way it will be seen that after the machine is once set, there is no danger of the operator bringing the grinding wheel up too far by power or of stopping short of the proper position to commence to finish the work. As has been stated, when reciprocating the grinding wheel by power, the spinning around of the rotary handle can be prevented simply by pulling out the flange 35.

Although I have illustrated and described only a single form of the invention and shown as applied only to a single type of grinding machines, I am aware that the in-

vention is capable of being carried out in many other ways and applied to practically all types of grinding machines and therefore I do not wish to be limited in these respects, but

What I do claim is:—

1. In a cylindrical grinding machine, the combination with a bodily movable grinding wheel, of power operated means for moving it toward and from the work, a movable stop for preventing the operation of the power operated means in one direction, and means for operating the stop whenever the wheel reaches a predetermined position, for disconnecting the wheel from the power. 70

2. In a cylindrical grinding machine, the combination with a bodily movable grinding wheel, of power operated means for moving it toward and from the work, a double faced clutch for connecting the wheel with said power operated means, and means for preventing the operation of the clutch in one direction. 85

3. In a cylindrical grinding machine, the combination with a grinding wheel movable toward and from the work, of means adapted to be set when the wheel is at one extreme, and means for returning said means to its set position whenever the wheel returns to said extreme position for preventing the wheel from moving beyond that extreme. 95

4. In a cylindrical grinding machine, the combination with a grinding wheel movable toward and from the work, of means for moving said wheel in either direction, means adapted to be set when the wheel is at one extreme for preventing the wheel from moving beyond that extreme on any subsequent operation, said means comprising a movable member which when so set prevents the operation of said wheel moving means in one direction, and means for bringing said movable means back to the same position whenever the wheel is in the same extreme position. 105

5. In a cylindrical grinding machine, the combination with a movable grinding wheel, of a feed drive shaft, a shaft for moving said wheel, means for transmitting power in either direction to the last named shaft from the feed drive shaft, said means comprising a double faced clutch, hand operated means for operating the double faced clutch, and means for preventing the clutch from moving to one closed position. 115

6. In a cylindrical grinding machine, the combination with a movable grinding wheel, of a feed drive shaft, a shaft for moving said wheel, means for transmitting power in either direction to the last named shaft from the feed drive shaft, said means comprising a double faced clutch, means connected with the second shaft for preventing the clutch from moving to one closed position. 125

tion when said second shaft has turned to a position to bring the wheel into a predetermined extreme position.

7. In a cylindrical grinding machine, the combination with a grinding wheel movable toward and from the work, of means adapted to be set when the wheel is at one extreme for preventing the wheel from moving beyond that extreme, said means comprising a shaft for moving the wheel, a wheel rotatable by said shaft and having a friction surface, a wheel having a friction surface adapted to engage the first named friction surface and rotate therewith, and means rotatable with the last named wheel for preventing the motion of the grinding wheel beyond a predetermined point in one direction.
8. In a cylindrical grinding machine, the combination of a bodily movable grinding wheel, a shaft for moving the grinding wheel, differential gearing connected with said shaft, a gear operated by said gearing, a wheel rotatable on the same axis as said gear, and having means for limiting the motion of the grinding wheel in one direction, and means for clamping said rotatable wheel to the gear, whereby the limiting position of the grinding wheel will be fixed.
- 30 9. In a cylindrical grinding machine, the combination with a grinding wheel movable toward and from the work, of means adapt-

ed to set when the wheel is at one extreme for preventing the wheel from moving beyond that extreme on any subsequent operation, hand operated means for independently moving the grinding wheel, and means for disconnecting the hand operated means from the grinding wheel.

10. In a cylindrical grinding machine, the combination with a bodily movable grinding wheel, of means for moving the grinding wheel by hand, means for moving the grinding wheel by power, and means for disconnecting the hand operating means from the grinding wheel.

11. In a cylindrical grinding machine, the combination with a bodily movable grinding wheel, of means for moving the grinding wheel by hand, means for moving the grinding wheel by power, means for disconnecting the hand operating means from the grinding wheel, means for disconnecting the power operating means from the grinding wheel, and means for connecting the proper operated means to move the wheel in either direction.

In testimony whereof I have hereunto set my hand, in the presence of two subscribing witnesses.
